UNITED STATES PATENT OFFICE.

GEORGES KLEIN, OF PARIS, FRANCE.

COUNTERBALANCING MEANS FOR MOVABLE DEVICES.

Application filed December 28, 1923, Serial No. 683,263, and in Belgium January 2, 1923.

This invention relates to counterbalancing means for movable devices under the control of resilient systems and refers more particularly although not exclusively to means for counterbalancing the sashes of the windows of vehicles, as this is the practical application of the invention which appears to offer the greatest advantages.

The object of the invention is so to construct means of the class in question that they are more simple and so that they enable the device which is to be counterbalanced to be operated with relatively small power.

According to the general principle of the invention the counterbalancing means comprises at least one group of parts adapted to oscillate and a corresponding resilient system, one extremity of which system is fixed. The group of parts is constituted by a two armed lever adapted to oscillate around a fixed pivot. To the arms of this lever are pivoted respectively the movable extremity of the resilient system, and one end of a connecting link. The other end of this connecting link is pivoted to a lever arm in rigid connection with the arm which supports the device to be counterbalanced. The two last mentioned arms are adapted to oscillate around a fixed pivot. The whole arrangement is such that whatever may be the position as regards its height of the device to be counterbalanced and the angular position of the oscillating group of parts, the device is substantially in equilibrium and is adapted to be maneuvered with very little force.

The invention also comprises certain other constructional details which are preferably utilized at the same time and which will be more fully explained hereafter.

In order that the invention may be more clearly understood, it will now be described with reference to the accompanying drawings, but it is to be observed that the description and drawings are given merely by way of example.

Fig. 1 of these drawings shows in diagrammatic elevation a complete mechanism mounted in the window casing of a vehicle and adapted to permit the sash being counterbalanced in the manner provided for by the invention.

Figs. 2, 3 and 4 show to a larger scale

and as to a part respectively in elevation, in developed section on 3-3, Fig. 2, and in end view, a portion of the mechanism.

The particular application illustrated in the drawings is the one in which it is desired to counterbalance the sash *a* of the vehicle in all positions which it can occupy as to its height, and so that it can be very easily raised and lowered.

b is a species of framework on the interior of which is mounted a group of parts adapted to oscillate between two plates *c* fixed at each side of the frame. The group of parts is connected on the one hand to the sash *a* and on the other hand to a resilient system, formed in the present case with helical springs *d* which have their axes parallel to one another. The springs may have their axes in the same plane or in two or more planes parallel to one another and in the latter case may be arranged in staggered or quincuncial formation.

The extremities of the springs are fixed respectively to two pieces *d*¹ and *d*². The piece *d*¹ is hinged as will be seen in connection with the group of parts, and the other *d*² is fixed to the frame *b* and is provided advantageously with means for permitting the initial tension of the springs to be regulated.

The oscillating group of parts comprises a lever *f* with two arms mounted on a spindle *c*¹, pivoted to the plates *c*. This lever is provided towards its extremities with two pivots *f*¹ and *f*², parallel to the spindle *c*¹. *g* is a lever arm carried by and rotating with a spindle *c*² which is also carried in bearings in connection with the plates *c*. The free end of this arm *g* is provided with a pivot pin *g*¹ parallel to the spindle *c*².

h is a connecting link pivoted at one end to the pivot pin *f*² of the lever *f* and at the other end to the pivot *g*¹ of the lever *g*.

e is another lever arm mounted upon and rotatable with the spindle *c*². At its outer or free end this arm *e* is adapted to support the sash *a*, preferably with the intervention of a grooved pulley.

The piece *d*¹ to which are connected the movable extremities of the springs *d* is pivoted to the pivot *f*¹ of the lever *f*.

The whole device is so arranged that the

framework *b* with the parts which it carries can be conveniently located and fixed in the sash casing as shown at Fig. 1. The pulley at the end of the supporting arm *e* is always in contact with the lower edge of the sash whatever the position as regards height occupied by the latter.

When the oscillating arm *e* turns downwards it tenses the springs *d* by means of 10 the arm *g*, the connecting link *h* and the lever *f*.

With the various parts properly proportioned and mounted as previously explained, the operation is substantially as follows:—

15 When the sash *a* is moved downwards it causes the arm *e* also to oscillate downwards. Through the spindle *c*² this causes the lever *g* to oscillate through a like angle. The connecting link *h* being operated by the 20 lever arm *g* causes the lever *f* to oscillate and this in turn moves the piece *d*¹ in the direction in which the tension of the springs *d* is increased.

When the sash *a* is raised it is assisted 25 by the supporting arm *e* which then oscillates towards the upper position through the action of the springs *d* operating through the group of oscillating parts, the movements in this case being the reverse of those 30 previously described.

With this construction if care be taken properly to choose the distances between the fixed pivotal axes *c*¹ and *c*² and the movable pivotal axes *f*¹, *f*², *g*¹, the length of the connecting link *h*, so that a certain functional relation is established with regard to the weight of the sash and the power of the springs employed, then for each position as regards height which can be occupied by the 40 sash there is such a relation between the different lever arms that the power given out by the springs when finally exerted under the sash supplies a force which is substantially sufficient to compensate for the 45 weight of the sash. Under these conditions the sash can be maneuvered with the greatest facility, and when left to itself at any point of its path of travel will remain in equilibrium. This result moreover is obtained with 50 very simple mechanism and one in which the springs occupy a minimum amount of space. As can be seen in Fig. 2, the lever *g* is connected to spindle *c*² by an ordinary set screw so that the angular relation of members *g* 55 and *f*, and hence the length of the link *h* which is utilized, may be varied.

It will be appreciated that the oscillating members can be otherwise constructed than as described; in connection with the drawing, for example, a construction is illustrated in which the supporting arm *e*, the lever *f* and the lever *g* are duplicated, the connecting link *h* being single. Their method of interconnection can be clearly observed 60 from the drawing.

In place of counterbalancing the sash by a single mechanism as described, a larger number of mechanisms might be employed, for instance two as illustrated at Fig. 1.

It is to be understood generally that the 70 invention is not limited to the particular constructional embodiments which have been illustrated, or described. It includes all modifications coming within a fair interpretation of the claims.

Amongst these modifications may be mentioned the one in which the relative positions of the pivotal axes of the oscillating devices are so modified that at the end of its path of travel the sash is not absolutely in equilibrium.

For instance there may be a slight excess of upward pressure tending to keep the sash closed. Or again, in the case of a sash with fastening means for holding the same closed 8 there may be a tendency on disengaging the fastening for the sash to drop slightly before the buffering action of the spring mechanism comes into play.

What I claim and desire to secure by Letters Patent of the United States of America is:—

1. In a counterbalancing apparatus, spring means having a movable end, a pivoted bell-crank lever mounted on a spindle below which its arms extend and having one arm thereof connected to said movable end, the other arm of said lever being connected to a link, said link being connected to a pivoted lever mounted on a spindle located below said first-mentioned spindle, said last-mentioned lever being adapted to turn in unison with an arm which is adapted to contact with the body to be counterbalanced.

2. In a counterbalancing apparatus, an arm mounted upon a first spindle and adapted to contact at the upper end thereof with the body to be counterbalanced, a second arm adjustably mounted on said first spindle, the adjustable connection of said second arm on said spindle permitting the variation of the angle between said arms, a bell-crank lever mounted upon a second spindle located above said first spindle, spring means having a movable end connected to one of the arms of said bell crank lever, and a link connecting the second arm mounted on said first spindle to the other arm of said bell crank lever.

3. In a counterbalancing apparatus, the combination of a pair of fixed spindles arranged one above the other, a pair of arms mounted upon the lower spindle and being relatively adjustable so that the angle between them can be varied, a bell-crank lever mounted upon the second and upper spindle and having its arms normally below the upper spindle, a link connecting one arm of the said bell-crank lever to one of the arms mounted upon the lower spindle, and

spring-actuated means attached to the second arm of the said bell-crank lever.

4. In a counterbalancing device a pair of spindles, a pair of arms mounted in adjustable angular relation to one another on one of said spindles, a bell-crank lever mounted on the other of said spindles, a link connecting

one of the arms of said bell-crank lever to one of the arms mounted on said first spindle, and spring actuated means attached to the second arm of said bell-crank lever.

In testimony whereof I have hereunto set my hand.

GEORGES KLEIN.
